UNITED STATES PATENT OFFICE.

THOMAS J. FRABER, OF WASHINGTON, DISTRICT OF COLUMBIA.

METALLIC STUDDING.

1,210,297.

Specification of Letters Patent. Patented Dec. 26, 1916.

Application filed May 24, 1916. Serial No. 99,604.

To all whom it may concern:

Be it known that I, THOMAS J. FRABER, a citizen of the United States, residing at Washington, in the District of Columbia, have invented new and useful Improvements in Metallic Studding, of which the following is a specification.

The invention relates to studding, and more particularly to the class of metallic studding for use in forming partitions such as walls, ceilings and the like for building construction.

The primary object of the invention is the provision of a studding of this character wherein the construction thereof is novel in form so that the metallic lathing, plaster boards or other facing materials can be secured in place and the plaster or finishing of the wall or ceiling interiorly of a building construction can be executed with dispatch as well as assuring neatness to the finished work.

Another object of the invention is the provision of a studding of this character wherein the same is desired for use as such or for a furring strip to be hung upon girders or can be used for the formation of partitions such as walls or the like and the metallic lathing or plaster boards or other wall facing materials will be firmly held in place and secured by the studding.

A further object of the invention is the provision of a studding of this character wherein the same can be made from a single piece of material bent into the required form and has cut therefrom tongues or ears which serve for the fastening of the metallic lathing or plaster boards or any other substance for the surfacing in the formation of a wall or ceiling.

A still further object of the invention is the provision of a studding of this character which is extremely simple in construction, thoroughly reliable and efficient in its purpose, strong, durable and inexpensive in manufacture and installation.

Other objects will be in part obvious and in part hereinafter set forth.

The invention accordingly consists in the features of construction, combination of elements and arrangement of parts which will be exemplified in the construction herein-after described, and the scope of the application of which will be indicated in the appended claim.

In the accompanying drawings: Figure 1

is a fragmentary perspective view of a studding constructed in accordance with the invention; Fig. 2 is an enlarged transverse sectional view thereof; Fig. 3 is a fragmentary perspective view of a portion of a partition or wall embodying the invention; Fig. 4 is a fragmentary perspective view of a modified form of studding; Fig. 5 is a fragmentary side elevation of the studding shown in Figs. 1 to 3.

Similar reference characters indicate corresponding parts throughout the several views of the drawings.

Referring to the drawings in detail, and more particularly to Figs. 1, 3 and 5, A designates a stud which is made from sheet metal. The stud A comprises a longitudinal central U-shaped portion 5 which extends the length of said stud and has lateral side flanges 6, one of which is formed with an inwardly extending parallel continuation 7 which is bent on itself to provide a wing 8 at right angles to the continuation 7 of the flange 6 and is disposed centrally of the U-shaped portion 5, while the continuation 7 of said flange 6 next to the wing 8 is formed with an angular portion 9 which insets the wing 8 within the hollow of the U-shaped portion 5 to contact with the inner surface 85 thereof at right angles to the said wing. The U-shaped portion 5 of the stud is cut at intervals medially thereof to form bendable tongues 10 which serve as fasteners for the metallic lathing 11 as these tongues are punched outwardly relative to the portion 6 to engage with the lathing 11 for supporting the same and are adapted to be bent back or over the lathing so as to hook or clinch it firmly in place upon the stud. It 95 is of course understood that the lathing carries the plastic facing for the wall as usual. The studs are set up in position and the lathing is placed against the same and the tongues 10 pass through the perforations in the lathing, whence finally the said tongues are bent over or backward so as to clinch the lathing and hold the same to the studding, it being understood of course that the studs are set up in vertical position and 100 are held in place in any suitable manner or are disposed and held in the ordinary well known manner.

In Fig. 4 there is shown a slight modification of the invention wherein the U-shaped portion 12 has cut and stamped therefrom at intervals diagonally opposed bendable

ears 13, while in conjunction with the portion 12 and the side flanges 14 seats 15 are provided to accommodate plastic boards 16 and the ears 13 are bent outwardly to overlap the edges adjacent thereto of the boards 15 to hold the same fast and in place relative to the studding, as will be obvious.

The wing 8 in Figs. 1 to 3 and the wing 17 in Fig. 4 are formed with apertures 18 at intervals therein so that when the occasion demands the said studs can be used as a furring strip for the hanging of the same upon girders by the passing of suitable fasteners through perforations 18 in the wings 15 for the suspension of the furring strip.

It is of course to be understood that the invention is not restricted to the particular location, manner of formation and the adaptation of the tongues 10 and ears 13 as the same may be changed within the scope of the appended claim.

From the foregoing description, taken in connection with the accompanying drawing,

the construction and manner of use of the herein described studding will be readily apparent and, therefore, a more extended explanation has been omitted.

Having thus described my invention, I claim:

A stud comprising a U-shaped portion 30 having side flanges made from sheet metal, one of said flanges being formed with a continuation parallel therewith and bent inwardly in the direction of the U-shaped portion, a wing formed on the continuation 35 at right angles thereto and provided with an angular portion, the angular portion of the wing insetting the wing centrally within the U-shaped portion, integral fastening protuberances projecting from the U-shaped 40 portion, said wing being formed at intervals with apertures.

In testimony whereof I affix my signature.

THOMAS J. FABER.
